UNITED STATES PATENT OFFICE

ROBERT W. VARDEMAN, OF INDEPENDENCE, MISSOURI

FOUNTAIN TOOTHBRUSH

Application filed May 28, 1928. Serial No. 281,191.

This invention relates to tooth brushes and more especially to a tooth brush serviceable for the massaging of the gums without the possibility of accidentally breaking the skin and perhaps causing infection, as is always a possibility where an ordinary bristle brush is employed, brushes having the massaging effect in addition to the tooth cleaning effect, being made of rubber or its equivalent. The rubber brushes mentioned are however, as open to objection from a hygenic standpoint, as the old or bristle type of brush.

Accordingly, it is the object of the invention to produce a tooth brush suitable for either cleaning and massaging operations and in one type for both, and which when not in use can be protected from contamination and in that condition, be carried in one's pocket or in a suitable touring case. A further object is to provide a so-called fountain type of brush in which the brush elements form a part of a paste holder but normally is so disposed that its teeth are not accessible to the paste and hence cannot be accidentally charged with the latter.

A further object is to provide a fountain brush as an attachment for a conventional tooth-paste tube, but of such construction that compression alone of the tube shall not be effective to charge the toothed portion of the brush with paste, as a provision against the escape of paste should the device be accidentally dropped or subjected to pressure.

Another object of the invention is to produce a fountain brush of the type outlined at low cost so that, if desired, it may be unitary or permanently associated with a paste tube, and be cast aside when the latter is empty, though it will be understood that a brush of the character under consideration may be used with any number of paste tubes if the cost is such that there would be a substantial economic waste in providing each paste tube with the brush attachment.

With the objects mentioned in view, the invention consists in certain novel and useful features of construction and combinations of parts, as hereinafter described and claimed; and in order that it may be fully

understood, reference is to be had to the accompanying drawing, in which:

Figure 1 represents an elevational view of a fountain brush embodying the invention with the toothed portion of the brush incased in an air-tight cap.

Figure 2 is an enlarged view partly in central longitudinal section, with cap omitted.

Figure 3 is a section taken on the line III—III of Figure 2.

Figure 4 is a fragmentary central longitudinal section of a modified construction.

Figure 5 is a larger sectional view of the construction shown by Figure 4, and taken on the line V—V of the latter.

Figure 6 is a cross section taken on the line VI—VI of Figure 4.

Referring to the drawing in detail, 1 indicates a conventional tooth-paste tube of the compressible or collapsible type, and 2 is a brush which in the preferred form is entirely made of relatively soft rubber or the like, the shank and head of the brush having a longitudinal bore 3. In Figures 1 to 3 inclusive, the bore is shown as of angular form in cross section, and fitting in the bore so as to be immovable with the brush and to stiffen it is a two-part stiffening device or tube, and the brush has an orifice 4 leading from the bore of the head and tube to the toothed surface.

The stiffening tube fits in the bore so as to be immovable with respect to the brush, and has an internal thread 6 at the shank end of the brush for screwing upon the threaded nipple 7 of the paste-charged tube. The tube 5 also has an orifice 8 registering with the orifice 4.

A tubular plug 9 fits tightly and non-rotatably in the tube 5 and closes the outer end of the same and likewise stiffens the outer end of the head of the brush, and the tubular portion of said plug has an orifice 10 normally held out of register with the orifice 8 through the resiliency of the brush-head, the arrangement being such that when the paste-tube is grasped, and pressure is applied on the head end of the brush, the squeezing action thus applied causes the resilient brush to yield and the plug to advance into the tube 5 until the

orifice 10 of the former registers with the orifice 8 of the tube 5. Assuming in this action that the tube and hollow portion of the plug are completely filled with paste and that 5 the latter cannot back-up in the paste tube 1, a charge of paste must pass through the registering orifices 8, 10 and 4 to the toothed face of the brush, and upon the removal of the pressure on the end of the head of the brush, 10 the latter reacts and thus withdraws the plug to its original position and cuts off the further escape of paste through the orifices mentioned, it being of course understood that the plug 9 bears an immovable relation to the head of the brush by being molded or otherwise tightly secured therein so that the plug shall move in one direction under the compressive action and in the opposite direction under the reactionary action of the 15 resilient brush.

After the pressure is removed as described, the brush can be handled in the usual manner for cleaning the teeth and for massaging the gums, and the latter operation can be 20 performed without danger of scratching or cutting the gums and hence with practically no danger of the gums becoming infected. When the use of the brush is discontinued, it can be readily cleansed in water or otherwise 25 and the cleansing agent cannot enter and contaminate the charge of paste within the tube, and as the paste is used up, the base of the paste tube will be folded or rolled as customary and as indicated at the right hand end 30 of Figure 1, for the purpose of keeping the stiffening tube fully charged so that a discharge of the paste can always be effected by applying pressure, as explained, on the head end of the brush.

40 The drawing indicates the tube of proportionately much greater diameter and length than is necessary, so that if it is desirable to discard the brush with the emptied paste tube, there will be but a small quantity of paste 45 within the stiffening tube to be wasted. However, if when a paste tube is emptied it is replaced by a new one, any loss of paste remaining in the stiffening tube will be relatively small, as the total waste from all of 50 the paste tubes employed will be measured by the capacity of said stiffening tube.

In order that the brush may be completely sealed from the air when not in use, it is desirable to provide a glass, celluloid or equivalent cap 17 to fit over the brush element and engage the base of the same with an air-tight relation, and for convenience in accomplishing this result, the base of the brush stem may be equipped with a flange 18 so that the open 60 end of the cap may be forced upon and grip the same sufficiently to avoid accidental dislodgment.

In the modified type of construction shown by Figures 4, 5 and 6, it is preferred that the bore of the brush shall be circular in cross

section and the tube and plug numbered respectively in this instance 11 and 12, of corresponding contour, and in this case it is desirable that the outer end of the plug shall be flattened as at 13, so that if the head end of the brush be grasped and twisted or turned, corresponding movement of the plug shall occur. In this case the plug 70 preferably fits over the head end of the tube 11 and has an orifice 14 normally in communication with the orifice 4 of the brush and out of engagement with an orifice 15 in the tube 11, the arrangement being such that the turning or twisting of the head end of the brush shall result in bringing its orifice and the registering orifice 14, in communication with the orifice 15 of the tube 11, and while holding the parts in this position compression is applied on the tube 1 so that a charge of paste 75 will be forced out through the registering orifices 15, 14 and 4 to the toothed face of the brush. To insure proper registration of the orifices 14 and 15, a pin-and-slot connection 16 is provided for the tube 11 and the plug, this connection arresting the twisting movement of the plug at the moment the three orifices are in full alignment. When the twisting pressure is removed, the reaction of the 80 resilient brush restores the parts to their original relationship and thus inhibits the escape of any additional paste even should the pressure on the tube be continued. It will thus be seen that in both cases a predetermined amount of paste is discharged, and that if a greater amount is desired the action 85 described must be repeated.

While it is a very desirable feature of the invention to provide the rubber brush head with resilient rubber teeth for convenience of massaging the gums without injury thereto, it will be apparent that the tooth face of the brush head may of any conventional character without affecting or impairing the required deforming action of said head to make provision for the charging of the teeth with 90 the cleaning agent.

From the above description, it will be apparent that I have produced a fountain tooth-paste brush which embodies the features of advantage set forth as desirable in the statement of the objects of the invention, and which may be changed in various particulars without departing from the principle and scope or sacrificing any of the advantages of 95 the appended claims.

I claim:

1. The combination with a resilient toothed brush head having a bore and an orifice leading from the bore to the toothed face of the brush, of a pair of tubes each fitting tightly in the resilient brush head and movable relatively to each other, one of said tubes having an orifice permanently communicating with the orifice of the brush head and the other constituting a feed tube and having an orifice 120 125 130

normally out of register with the orifice of the first-named tube but adapted to register therewith upon deformation of the resilient brush head by the application of force there-
5 to.

2. The combination with a resilient toothed brush head having a shank portion and a toothed face, the head and shank portions having a longitudinal bore and the former an
10 orifice leading from the bore to the toothed face, a stiffening tube within the bore of the head and shank, a compressible paste-charged tube communicating with the shank end of the stiffening tube, a hollow plug fitting in
15 the bore and communicating with the stiffening tube, the last-named tube and said plug being movable relatively and each fixedly se-
cured relative to the brush head, there being
20 an orifice in the said tube and plug with one of said orifices in permanent communication
with the orifice in the brush head and the other of said orifices normally out of aline-
ment but adapted to be brought into aline-
25 ment with the other orifice upon deformation
of the brush head upon the application of
force thereto so that upon compression of
the tube its contents will be discharged onto
said brush head.

3. The combination of a compressible paste
30 tube, a brush of resilient material having a toothed face, a longitudinal bore and an orifice leading from the bore to the toothed face, a stiffening tube in the bore having an orifice and secured at one end on the discharge end
35 of the compressible tube, and a hollow plug in the bore and in movable engagement with the stiffening tube and provided with an orifice; one of the last-named pair of orifices being in registration with the orifice of the
40 brush and the other to be brought into such registration by deformation of the brush head by applying force thereon so that upon com-
pression of the tube its contents will be dis-
charged onto said brush head.

45 4. A resilient toothed brush head having a longitudinal bore and an orifice leading from the bore to the toothed face of the brush head, and a feed tube in said bore having an orifice normally out of alinement with the orifice
50 in the brush head; said tube orifice and brush orifice being adapted to be placed in aline-
ment upon the application of force sufficient to deform the brush head, the orifices being automatically returned to normal relation
55 upon the release of such force.

In testimony whereof I affix my signature.
ROBERT W. VARDEMAN.
